UNITED STATES PATENT OFFICE.

FRANK BIRD, OF HAMILTON, NEW ZEALAND, ASSIGNOR TO BIRD'S PATENTS LIMITED, OF AUCKLAND, NEW ZEALAND.

OPERATING MEANS FOR FANLIGHTS AND THE LIKE.

Application filed November 18, 1927. Serial No. 234,221.

This invention relates to improvements in means devised for use in the operation of overhead fanlight sashes and the like, such as door transoms, skylights and all classes of sashes in which the sash is hinged along one edge or end and is opened and closed by means operating to swing the sash upon its hinges.

The said means are of such a nature as to provide for the opening movement being regulated to any amount within the limits provided for, and for the sash being firmly retained in its adjusted position. They are also of such a nature as to provide for the opening and closing movements of the sash being effected by the turning of a lever through the agency of a pull cord attached thereto.

The invention comprises a crank lever that is mounted on a pivot affixed to the main frame of the sash and is connected by a connecting rod with the sash itself so that a full half-turn of the crank lever will thrust open the sash to its limit and the remaining half-turn will draw it to the closed position again. This lever is combined with an operating lever mounted loosely on the same pivot and capable of being turned only through a fraction of a revolution, said operating lever being spring controlled to draw it normally upwards and being adapted to be turned downward against the action of the spring. The crank lever has a ratchet wheel combined therewith, and the operating lever has a pawl pivoted thereon that is adapted to engage with the ratchet wheel and turn it and the crank lever when the operating lever is turned, and thereby to rotate the crank lever by a series of movements through a full rotation to open and close the sash, the sash being adapted to remain at any position represented by the separate movements of the crank lever.

This construction of apparatus is illustrated in the accompanying drawings, in which:—

Figure 1 is a plan of the device showing the sash closed.

Figure 2 is a side elevation, and

Figure 3 a front elevation thereof, showing the sash partially opened as by the first movement of the crank lever.

Figure 4 is a sectional elevation on the line 4—4 of Figure 3 and looking to the left thereof.

Figure 5 is an inside elevation of the crank lever.

Figure 6 is an enlarged sectional elevation showing the manner of mounting the parts comprising the invention.

A represents the main frame of the structure and B the portion or member of the sash frame with which it is combined.

To the face of the frame A, a plate 10 is affixed, such plate having a journal 11 combined therewith to project from its face and from which journal a threaded stem 12 extends. Such stem is flattened, as at 13, on one side, for a purpose to be afterwards explained.

A crank lever 14 has a hollow boss 15 which fits over the stem 12 and surrounds the journal 11 with a neat fit so that it may turn thereon. This boss is pressed inward to make a frictional grip upon its journal that will serve to hold the crank lever at any point in its turning movement against any ordinary strain, by means of a washer 16 engaging its outside face and a spring presser plate 17 engaging the outside of the washer, both of which parts have holes shaped to engage the flat 13 of the stem 12 to keep them from turning, and a thumb nut 18 screwing on the stem and pressing the whole together. The frictional grip between the washer and the boss may be regulated by the said thumb nut to provide for any desired resistance against the turning of the crank operating lever.

The outer end of the crank lever 14 has pivoted to it one end of a connecting link or rod 19, the other end of which is pivoted in a bracket 20 that is made fast to the sash B at any approved distance out from its hinge.

These parts are so relatively arranged that when the crank lever 14 is turned to extend straight across from the sash B, the sash is drawn tightly to the closed position as in Figure 1. A half-turn of the crank through the lower part of its rotation will therefore cause the sash to be thrust open to the maximum amount allowed for, and the remaining half-turn through the upper part of its rotation will pull the sash back to the closed position.

The appliance embodies means for thus turning the crank lever through fractions of its full turn by the same action of the operative means, so that by a series of movements the sash may be opened and closed. The arrangement of these means, as shown in the

drawings, provides for four movements imparting a full turn to the crank lever, thereby allowing for the first movement half opening the sash, the second movement fully opening it, the third half closing it, and the fourth fully closing it. Other fractions may however be arranged for.

Such means consist in an operating lever 21 that has its boss 22 loosely journalled to turn upon the boss 15 of the crank lever and upon the inside thereof. This lever 21 is restricted to a quarter-rotation by means of a block 23 upon its inside face situated between blocks 24 and 25 fixed on the adjacent face of the bearing plate 10. A coiled spring 26 surrounds the boss 22 of the operating lever and serves to keep that lever normally raised to the upward limit of its movement, represented in dotted lines in Fig. 2 and to return it to such position when it is drawn down into its full-line position and then released. These blocks are clearly shown in Figure 4.

The crank lever 14, on its rear side, has a ratchet wheel 14^a formed in one therewith, and such ratchet wheel is adjacent to the front face of the lever 21. On such face a pawl 21^a is pivoted so that it is adapted to engage the teeth of the ratchet wheel 14^a when the lever 21 is pulled down against its spring, and to slide freely over it when the lever turns up. Thus a downward pull on this lever will turn the crank lever a portion of its rotation equal to the amount of movement given the operating lever, and the desired partial or full opening or closing of the sash will be obtained by a series of pulls.

For thus actuating this lever 21, a pull cord 27 is attached to its outer end and depends to within reach from the floor level below.

I claim:—

1. Fanlight or other hinged-sash operating means comprising a journal pivot secured to the main frame of the sash, a crank lever mounted upon such journal and having a ratchet wheel combined therewith, a connecting rod extending between the crank lever and the sash and pivotally attached thereto, an operating lever structually separate from and movable relatively to the crank lever and journalled on the said journal, a pawl pivoted on such operating lever and adapted to engage the said ratchet wheel when the operating lever is turned in one direction, and spring means for normally turning said operating lever in the reverse direction.

2. In a fanlight or other hinged-sash operating means according to claim 1, a stop piece on the operating lever, and two stop blocks fixed around the pivot thereof at distances apart and between which the said stop piece is positioned.

3. In a fanlight or other hinged-sash operating means according to claim 1, a bearing plate, a journal for the crank lever affixed to said plate, a hollow boss for the crank lever fitting over such journal, a threaded stem extending from the journal and passing through the crank lever boss, a spring actuated washer placed on such stem to engage the boss and held from rotation, and a thumb nut screwed upon the stem to engage such washer.

4. A fanlight or other hinged-sash operating means according to claim 1, in which the crank lever has a boss formed to provide a journal for the actuating lever.

In testimony whereof, I affix my signature.
FRANK BIRD.
